His Attorney.

UNITED STATES PATENT OFFICE

2,160,786

TUBULAR LAMP BASE

Conrad S. Peterson, Cleveland Heights, Ohio, assignor to General Electric Company, a corporation of New York

Application March 17, 1938, Serial No. 196,458

5 Claims. (Cl. 176—126)

My invention relates to electric lamps and similar devices, and more particularly to a base and socket construction for such devices. Still more particularly, my invention relates to a base and socket construction for electric lamps of the double-ended discharge type, in which a filamentary electrode is mounted at each end of the lamp.

In electric discharge lamps of the tubular double-ended type, it is necessary that each end of the lamp be provided with a suitable base to thereby properly mount the lamp. However, it is frequently desirable to mount a number of such lamps in axial alignment with each other so as to produce an extended line of light. To obtain the nearest approach to an uninterrupted line of light, it is essential that the longitudinal extent of the unilluminated portions at each end of the lamp, occasioned by the necessary base and socket construction thereat, be maintained at a minimum. Accordingly, one object of my invention is to provide a suitable base and socket construction for electric lamps of the tubular type which will be of minimum extent longitudinally of such lamp.

Another object of my invention is to provide a base and socket construction for electric lamps of the tubular double-ended type whereby the lamp may be readily inserted in its socket and securely locked therein so as to effectively prevent unwarranted or premature disengagement therefrom.

Still another object of my invention is to provide a suitable base and socket construction for double-ended lamps having a pair of current carrying leads at each end of the lamp whereby the said leads may be both connected in the proper manner in the lamp circuit.

A further object of my invention is to provide a base and socket construction for double-ended lamps in which the current-conveying members thereof are entirely concealed and unexposed when the base is assembled in its socket so as to prevent short circuits as well as injurious shocks therefrom.

A still further object of my invention is to provide a lamp base having a removable insert therein whereby the connection of the lamp filament or electrode leads to the contact members of the base may be accomplished in a convenient and simple manner.

Further objects and advantages of my invention will appear from the following description of a species thereof and from the accompanying drawing.

In the drawing, Fig. 1 is a side view, partly in section, of a tubular lamp base and socket construction comprising my invention, the bases being mounted on a lamp disposed in correct position preparatory to its insertion in the socket; Fig. 2 is an isometric view of one of the bases and sockets shown in Fig. 1 with the base insert removed and the socket partly broken away; Fig. 3 is a view of the inner end of one of the bases shown in Fig. 1; Fig. 4 is a sectional view on the line 4—4 of Fig. 1; and Fig. 5 is an enlarged fragmentary view of a modified form of lamp base according to my invention.

Referring to the drawing, the base and socket construction there illustrated is shown mounted on and arranged to receive an electric lamp 10 of the tubular double-ended discharge type having a filamentary electrode 11 at each end, each electrode being coated with an electron-emissive material. Each electrode is provided with a pair of leads 12, 13 through which current is passed to preheat the electrode.

The base 14 according to my invention comprises a molded cup-shaped body or shell 15 of suitable insulating material, preferably Bakelite, and consists of a bottom or end wall 16 and a cylindrical wall 17. The said cylindrical wall is of the proper internal diameter to fit loosely over the end or neck portion 18 of the lamp envelope 19, to which portion the base is united by suitable cement 20. The base body 15 is formed with an integral socket-engaging tab 21 extending from the cylindrical wall 17 of said body. The tab 21 is made of the same material as the body 15, being molded therewith, and consists of a disc-shaped portion 22 connected to the body 15 of the base by a relatively narrow neck portion 23. Molded to the inner surface 24 of the base end wall 16 and extending through and outwardly beyond the cylindrical wall 17, are a pair of contact strips 25, 26, preferably of brass. The outwardly extending portions of the strips 25, 26 are curved so as to provide arcuate portions 27 conforming to and molded to the edges 28 of the tab 21. The outer ends of the arcuate portions 27 terminate short of each other, being separated by a spacing lug 29 on the tab 21. If desired, the said outer ends of the arcuate portions 27 may be bent inwardly, as shown at 27' in Fig. 5, whereby the spacing lug 29 definitely prevents separation of the arcuate portions 27 from the edge 28 of the tab. Where the base 14 is one for use with a lamp of a relatively large diameter, the cylindrical wall 17 is provided with an outwardly extending

positioning lug or ear 30 suitably shaped to engage a co-operating surface on the lamp socket to thereby properly space the lamp from its fixture.

5 To permit easy attachment of the electrode leads 12, 13 to the base contact strips 25, 26, the end wall 16 of the base is provided with a centrally located and circular removable insert 31. The base 14 is first cemented in place on the end 10 of the lamp with the said insert 31 removed. The opening 32 in the base end wall 16 thus provides ready access to the interior of the base and exposes the two contact strips 25, 26 extending across the inner surface of the end wall. The 15 two electrode leads 12, 13 can thus be very easily soldered or welded to the two contact strips 25, 26 respectively, as shown in Fig. 2. The insert 31 is then replaced in the opening 32 in the base end wall 16. If desired, the insert may be colored to 20 thereby indicate the color of the light emitted by the lamp during operation. This feature is particularly advantageous in the case of fluorescent discharge lamps in which the fluorescent material coated on the glass envelope may be of a different color from the actual color of the light emitted 25 during operation of the lamp.

The socket 33 for co-operation with the above-described base 14 comprises a hollow body 34 of insulating material, preferably Bakelite, a pair 30 of spring contact members 35 mounted therein, and a rear cover plate 36 riveted to the body portion 34. The said body portion is formed with a forwardly extending hollow projection 37 the front surface 38 of which is curved to conform to 35 the curvature either of the cylindrical wall 17 of the lamp base 10 (in the case of the smaller diameter lamps), or to the curvature of the ear 30 on the lamp base (in the case of the larger diameter lamps). An opening or slot 39 in the body 40 portion 34 extending through the projection 37 is adapted to receive the tab 21 of the lamp base 10.

The contact members 35 are preferably made of phosphor bronze and are held in place against a positioning shoulder 40 in the socket by the rear 45 cover plate 36. As shown in Fig. 2, the rear surface of the socket body portion 34 is provided with grooves or channels 41 adapted to snugly receive the contact members 35 and so further 50 assist in positioning and supporting the contact members 35 in the socket, each of said members is provided with two forwardly extending lugs 42 and 43 (Figs. 1 and 2) spaced apart the proper distance to snugly receive a positioning 55 lug 44 in the socket body portion 34. Each contact member 35 is also provided with a spring finger 45 disposed in the slot 39 in the body portion 34 and extending forwardly into the projection 37. The forward extremities of the spring 60 fingers 45 are curved oppositely away from each other so as to form arcuate end portions 46 which are adapted to spring over and engage the arcuate portions 27 of the base tab 21 upon insertion thereof in the socket.

65 As shown in Fig. 1, the two sockets 31, 31 are preferably mounted on a suitable fixture 47, being spaced apart the proper distance to freely receive the base tabs 21 in the slots 39. The socket contact members 35 are connected to the circuit 70 by leads 48, 48 which may be either soldered directly to the lugs 43 or attached thereto by screws 49 threaded into said lugs.

To insert the lamp 10 in the sockets 33, 33, the lamp is simply placed in the position shown in 75 Fig. 1, with the base tabs 21 opposite the socket

slots 39, and then moved toward said sockets so that the tabs 21 enter said slots. The insertion of the tabs 21 spreads the spring fingers 45 apart until the arcuate portions 46 thereof snap over the corresponding arcuate ends 27 of the base 5 contact strips 25, 26 to thereby securely lock the base tabs in the sockets. The engagement of the arcuate portions 46 of the spring contact fingers 45 with the arcuate ends 27 of the base contact strips 25, 26 accordingly connects the latter to the 10 lamp circuit and at the same time provides a positive lock against unwarranted or premature disengagement of the lamp from the socket.

What I claim as new and desire to secure by Letters Patent of the United States is:

15 1. A base for electric lamps and similar devices comprising a cup-shaped member of insulating material having an end wall, a cylindrical wall, and a disc-shaped tab extending outwardly from said cylindrical wall, and a pair of spaced contact strips secured to said member and extending across the inner surface of said end wall, said contact strips further extending through said cylindrical wall and being curved to conform to and engage the edge of said tab.

20 2. A base for electric lamps and similar devices comprising a cup-shaped member of insulating material having an end wall and a cylindrical wall, said end wall being provided with a removable insert, and a pair of spaced contact strips secured to said member and extending across the removable insert in said end wall and through said cylindrical wall.

25 3. A base for electric lamps and similar devices comprising a cup-shaped member of insulating material having an end wall and a cylindrical wall, said end wall being provided with a centrally located circular insert removable therefrom, and a pair of spaced contact strips secured to said member and extending across the removable insert in said end wall and through said cylindrical wall, the outer extremities of said contact strips being curved to provide oppositely disposed arcuate portions.

40 4. A base for electric lamps and similar devices comprising a cup-shaped member of insulating material having an end wall, a cylindrical wall, and a disc-shaped tab extending outwardly from said cylindrical wall, said end wall being provided with a removable insert, and a pair of spaced contact strips secured to said member and extending across the removable insert in said end wall, said contact strips further extending through said cylindrical wall and being curved to conform to and engage the edge of 45 said tab.

45 5. An electric lamp or similar device comprising a tubular envelope, a filament sealed within said envelope at each end thereof and having a pair of leads extending through said envelope, a base 50 mounted on each end of said envelope, each of said bases comprising a cup-shaped member of insulating material having an end wall provided with a removable insert, a cylindrical wall, a disc-shaped tab extending outwardly from said cylindrical wall, and a pair of spaced contact strips secured to said member and having portions extending across the removable insert in said end wall, the pair of lead wires adjacent each base being connected to said portions of the 55 contact strips, said contact strips further extending through said cylindrical wall and being curved to conform to and engage the edge of said tab.
